(57) **CLAIM**

The ornamental design for a wooden fence post support, as shown and described.

DESCRIPTION

FIG. 1 is a perspective view of a wooden fence post support showing my new design;

FIG. 2 is a side view (opposite side view is mirror image) thereof;

FIG. 3 is a front view thereof;

FIG. 4 is a back view thereof;

FIG. 5 is a top view thereof; and,

FIG. 6 is a bottom view thereof.

In FIG. 1, the broken lines showing of environmental structure for purposes of illustrating the wooden fence post support in a condition of use. The broken lines and the structure they depict form no part of the claimed design.
